UNITED STATES PATENT OFFICE.

HUGH SNOWIE JONES, OF HAMPSTEAD, LONDON, ENGLAND.

TREEING DEVICE FOR BOOTS AND SHOES.

1,388,046.

Specification of Letters Patent. Patented Aug. 16, 1921.

Application filed September 8, 1919. Serial No. 322,501.

(GRANTED UNDER THE PROVISIONS OF THE ACT OF MARCH 3, 1921, 41 STAT. L., 1313.)

To all whom it may concern:

Be it known that I, HUGH SNOWIE JONES, of "Carlton," Arkwright Road, Hampstead, in the county of London, England, have invented certain new and useful Improvements in or Relating to Treeing Devices for Boots and Shoes, for which I have filed an application in Great Britain, May 16, 1917, Patent No. 112,231, of which the following

10 is a specification:—

This invention has reference to treeing devices of the kind comprising a front or foot portion and a rear or heel portion jointed together by an adjustable intermediate link device embodying a spring, the front or foot portion being designed to fit the forward portion of a boot or shoe, including the instep and toe portions thereof, and the rear or heel portion to fit against the heel of the boot or shoe, the intermediate link device serving to admit of the treeing device being inserted in the boot or shoe (hereinafter referred to as a boot) and the spring serving to keep the parts of the device and the boot in which they are inserted, in the desired expanded or stressed condition.

Now the present invention has reference, in treeing devices of the kind referred to, 30 to a simple and effective construction and arrangement of the intermediate link device and of the arrangement and actuation of the spring.

For this purpose in a treeing device according to the invention, the foot and heel portions of the device are connected together by an intermediate multiple link arrangement, such that upon the device being moved into its operative position the front 40 member of the multiple link arrangement will be caused to assume a more or less horizontal position and the rear link to assume a more or less vertical position thereby compressing the spring which acts to force 45 the foot and heel portions of the device apart and subject the boot to the desired treeing action. According to one example, the intermediate multiple link arrangement 50 may comprise two links, namely a front one and a rear one, the latter being preferably in the form of a plate. The spring inclosed in the heel portion of the device is arranged to be compressed by the rear link when the device is placed in a boot and the front heel

portions forced apart. The plate-like link 55 may conveniently be connected to the heel portion of the device by jointing it at its upper end to a second plate fixed to the front side of the said heel portion and formed with a hole through which extends 60 a flanged plunger for compressing the spring when the movable hinged plate is pressed toward the fixed plate. The two plates in this case form an ordinary butt hinge.

To render a treeing device according to the invention adjustable for boots of different lengths, the link can be made in two parts capable of sliding endwise relatively to one another and of being readily fixed in 70 their adjusted position, by a spring actuated pin. The two parts of the link may be arranged to slide one within the other, telescopically, or one against the other, side- 75 wise.

To admit of the foot and heel portion of the treeing device with intermediate link arrangement being folded up one against the other to facilitate packing, the foot portion of the device may be made more or less 80 concave on and along its underside to accommodate the heel portion and link arrangement.

As will be obvious, a treeing device according to the invention can be constructed 85 in various forms.

In the accompanying illustrative drawings, Figures 1 and 2 show respectively in side elevation and central longitudinal section, one construction of treeing device according to the invention.

Fig. 3 is a cross sectional elevation on the line A, A, of Fig. 1. Fig. 4 shows the position of the parts of the device folded up for packing.

Referring to Figs. 1 to 4, *a* is the foot portion, *b* the heel portion and *c* and *d* the front and rear links of an intermediate double link arrangement. The front link *c* is jointed by a pin *e* to the foot portion *a* and 100 the rear link *d* is jointed by a pin *f* to the upper part of a plate *g* fixed to the front side of the heel portions *b*, the two links being jointed together by a pin *h*, the arrangement being such that the rear link *d* can 105 assume a more or less vertical position as shown in Fig. 1. The rear link *d* is in the form of a plate jointed to the plate *g* by the

pin *f* the two plates and pin resembling an ordinary butt hinge. *i* is a coiled spring housed in a recess *j* in the heel portion *b* and *k* is a push device the inner end of which is 5 flanged and bears against the spring and the outer end of which extends through a hole *m* in the plate *g* so that it can be pressed inward, to compress the spring *i*, when the plate link *d* is moved down against it. The 10 push device *k* may be recessed at its inner side and the forward end of the spring *i* be arranged to extend into it.

The front link *c* comprises two tubes arranged to slide telescopically one within the 15 other, the inner tube carrying a spring pressed pin *n* adapted to enter any one of a series of holes *o* in the outer tube. The arrangement is such that by pressing in the pin *n* by a finger against the action of its 20 spring *n*¹, the two parts of the link can be moved endwise relatively to one another and the pin allowed to reenter another hole *o* and firmly hold the said parts in their adjusted position. The front end of the inner 25 tube and the rear end of the outer tube are adapted to be jointed by the pins *e* and *h* to fixed lugs *p* and *r* on the foot portion *a* and link *d* respectively. *s* is the ordinary finger piece fixed on the foot portion *a* to facilitate 30 removal of such portion from a boot.

The foot portion *a* is hollowed out on its underside to form a cavity *t* for the reception of the multiple link arrangement *c*, and heel portion *b*.

The foot and heel portions *a* and *b* may be 35 of wood and the remaining portions of the device be of metal.

I claim.

1. In combination with the front and heel members of a boot tree, a link pivotally connected to the front member, a plate hingedly connected at its upper end to the rear member and also pivotally connected to said link, and a spring arranged in a recess in 40 said heel member and exerting tension 45 against said plate to normally hold said plate at an angle with respect to said heel member.

2. In combination with the front and heel members of a boot tree, a link pivotally 50 connected at its front end to the front member, a plate hingedly connected at its upper end to the front side of said heel member, and also pivotally connected to the rear end of said link, a spring arranged in a recess in 55 said heel member, and a push device guided by said heel member and arranged to bear against said plate and also against said spring, so that said spring exerts its tension to normally hold the plate at an angle with 60 respect to said heel member.

In witness whereof I affix my signature in presence of two witnesses.

HUGH SNOWIE JONES.
